UNITED STATES PATENT OFFICE.

JAMES MEADE BROWN, OF ROSEBURG, OREGON.

SQUARE.

1,076,095.

Specification of Letters Patent.

Patented Oct. 21, 1913.

Application filed July 16, 1912. Serial No. 709,766.

To all whom it may concern:

Be it known that I, JAMES MEADE BROWN, a citizen of the United States, residing at Roseburg, in the county of Douglas and 5 State of Oregon, have invented a new and useful Square, of which the following is a specification.

This invention relates to squares, and aims to provide a device of the character 10 indicated which will serve either as an ordinary square, a try-square, or as a bevel or miter square, and which when not in use may be compactly folded together to be conveniently stored away or carried about in a 15 vest pocket or the like.

This invention also contemplates the production of a square of the class specified, which shall be simple, substantial, durable and inexpensive in construction, as well as 20 convenient, accurate and efficient in use, and which may be employed by draftsmen, carpenters, mechanics or other artisans.

With the foregoing general objects outlined, the present invention resides in the 25 novel construction and combination of parts hereinafter set forth and particularly claimed, it being understood that this device is susceptible of alterations or deviations in its details within the scope of the 30 appended claims without departing from the spirit of the invention.

The invention has been illustrated in its preferred embodiment in the accompanying drawings, wherein similar reference characters have been employed to denote corresponding parts, and wherein—

Figure 1 is a plan view of the square in 35 open position. Fig. 2 is a plan view of the square when folded, parts being broken away. Figs. 3, 4 and 5 are sectional details taken on the lines 3—3, 4—4 and 5—5 of Fig. 2, respectively. Fig. 6 is a perspective view of a number of details in separated position.

Referring specifically to the drawings, the present square embodies a stock or beam denoted generally by the numeral 7 and a tongue or blade 8 pivoted to the stock. The stock comprises a pair of rectangular cheek 40 plates 9 and the respective shim strips 10 and 11 riveted between the outer edges and outer ends of the cheek plates, the adjoining ends of the shim strips 10 and 11 being spaced apart to provide an opening 12 at 45 the outer end of the stock through which an implement may be introduced to swing the

blade 8 open should the same stick. The tongue 8 is of such dimensions as to fit snugly within the cheek plates 9 when the parts are folded. The cheek plates, tongue, 50 and shim strips may be constructed of Bessemer steel, or in fact, of any other material, which also applies to the remaining parts of the square hereinafter referred to. The various parts may also be polished or 55 otherwise ornamented or protected.

The tongue 8 is pivoted to the stock 7 by means of a pin or rivet 13 passing through the cheek plates 9 and the tongue 8 adjacent one corner of the inner end of the 60 stock, said pivot pin having its ends headed. This pivot pin 13 permits the tongue 8 to be folded within the stock and when the tongue is swung outwardly or into open position, the outer edge thereof is designed 65 to lie flush with the inner end of the stock when the tongue and stock are at right angles to each other.

The cheek plates 9 are each provided with an arcuate slot 14 at the inner end, which 70 slots have the pivot pin 13 as a center, and one of the cheek plates has a protractor scale 15 along one edge of the slot 14. This protractor scale may be provided with the usual degree of graduations running from 75 zero to 90°, and may be graduated to indicate pitches of various proportions, such as one-quarter, one-third, one-half, two-thirds, three-quarters and the like. A flat pointer 16 rests upon the cheek plate 9 having the 80 protractor scale, and is provided with an aperture at its butt end receiving one end of the pivot pin 13, the other end or tip of the pointer coöperating with the protractor scale 15.

In order to secure the pointer 16 relative 85 to the tongue 8 and in order to retain the tongue at any desired position, a square or non-circular bolt 17 is passed through the tongue and passes through the arcuate slots 14, the head 18 of the bolt bearing against the cheek plate opposite the one having the protractor graduations and the bolt having a screw-threaded reduced extension 19. The bolt 17 passes through a square or non-circular opening 20 in the tongue 8, and the screw-threaded extension 19 passes through an aperture 21 in the pointer 16 adjacent its free or pointed end, a projecting tail nut 22 being engaged on the threaded end of the 90 bolt and bearing against the pointer 16. It 105 will thus follow, that the bolt 17 prevents 110

the pointer 16 against movement relative to the tongue, so that the pointer stands transversely of the tongue and is swung with the tongue, and it will be further observed, that 5 by tightening the tail nut 22, the cheek plates will be clamped against the tongue 8 so as to clamp the tongue at any position to which it is set. Means have also been provided for locking the tongue relative to the 10 stock at certain positions, preferably when the tongue is at right angles to the stock and when the tongue is folded within the stock, these means consisting in a leaf spring 23 arranged along the inner edge of a cheek 15 plate 9 having the protractor scale, one end of the said spring being secured to the said cheek plate adjoining the pivot pin 13 by means of a rivet 24. The free end of the spring 23 has a catch or latch pin 25 secured thereto which works through apertures 26 20 provided in the cheek plates 9, the said catch being engageable through apertures 27 in the tongue 8, so that the catch 25 may snap through the respective apertures 27 when the 25 blade is swung at right angles to the stock and when the blade is folded within the stock. The edges of the tongue 8 are preferably provided with suitable scales or graduations.

30 The use of squares of this character is so common in the art, that an extensive description thereof is not thought necessary, the same being apparent to the various artisans. This square, however, possesses 35 a number of advantages as will be apparent, and carries out the objects aimed at in a satisfactory and convenient manner, the present square being a desirable one for the purposes for which it is designed.

40 Having thus described the invention, what is claimed as new is:—

1. A square embodying a stock comprising two elongated cheek plates; an elongated

tongue designed to be housed between the cheek plates; a pivot pin passing through 45 the cheek plates and the tongue at one corner; the cheek plates having arcuate slots therein with the pivot pin as a center; a non-circular bolt fitting through the tongue and 50 slots with its head bearing against one cheek plate, the bolt having a reduced threaded end; a pointer connected at one end to the pivot pin and at the other end to the reduced threaded end of the bolt; the other cheek 55 plate having a protractor scale coöperating with the pointer and a nut engaging the threaded end of the bolt to lock the pointer in an adjusted position on the protractor scale.

2. A square embodying a stock comprising 60 two elongated cheek plates and shim strips secured between one of the edges and one of the ends of the cheek plates; an elongated tongue designed to be completely housed between the cheek plates; a pivot pin passing 65 through the cheek plates and tongue at one corner; the cheek plates having arcuate slots therein with the pivot pin as a center; a non-circular bolt fitting through the tongue and slots with its head bearing against one cheek 70 plate, the bolt having a reduced threaded end; a pointer connected at one end to the pivot pin and at the other end to the reduced threaded end of the bolt; the other cheek 75 plate having a protractor scale coöperating with the pointer; and a tail nut engaging the threaded end of the bolt to lock the pointer in an adjusted position on the protractor scale.

In testimony that I claim the foregoing as 80 my own, I have hereto affixed my signature in the presence of two witnesses.

JAMES MEADE BROWN.
